UNITED STATES PATENT OFFICE.

ISAAC APPELBAUM, OF PHILADELPHIA, PENNSYLVANIA.

BLADE FOR FABRIC-CUTTING MACHINES.

Application filed December 14, 1922. Serial No. 606,773.

To all whom it may concern:

Be it known that I, ISAAC APPELBAUM, a citizen of the United States, residing in the city and county of Philadelphia, State of Pennsylvania, have invented a new and useful Blade for Fabric-Cutting Machines, of which the following is a specification.

My invention relates to a novel fabric or cloth cutting machine and more especially to machines of the reciprocating type, for cutting piled fabric, and to a novel construction of cutting blade or knife and a mounting therefor.

The invention further comprehends or consists of a novel construction in a blade and a mounting therefor, whereby the blade is steadied and positively guided in its movements to accurately cut the cloth or other fabric in piles; to render the blade reversible in use and to relieve the blade of longitudinal and lateral stresses to which it is subjected during the cutting action, and to compensate for inaccuracies or imperfections in the blade, especially where the same or its cutting edge or edges are not true, but are wavy or irregular, resulting particularly from the thin character of the blades.

The invention consists further of novel means for cleaning out a vertically extending guide channel in the guide-standard of the machine between the cheeks of which the knife or blade reciprocates up and down, so as to effectively prevent any binding due to the splaying out and disintegration of the material during the cutting action entering the guide channel, in addition to preventing the breaking of or injury to the blade and ensuring the free working thereof at all times.

A further object of the invention is to protect the inoperative cutting edge of the blade while the machine is in use, so that there will be no dulling or straining, and whereby an effective cutting action will be produced when the blade is reversed.

It further consists of other novel features of construction and advantage, all as will be hereinafter fully set forth.

For the purpose of illustrating my invention, I have shown in the accompanying drawings, a form thereof which is at present preferred by me, since it will give in practice satisfactory and reliable results, although it is to be understood that the various instrumentalities of which my invention

consists can be variously arranged and organized and that my invention is not limited to the precise arrangement and organization of these instrumentalities as herein shown and described.

Figure 1 represents a side elevation of the lower portion of a fabric cutting machine constructed in accordance with and embodying my novel invention.

Figure 2 represents a vertical section thereof.

Figure 3 represents a fragmentary, bottom plan view of the slide foot and channel of the machine.

Figure 4 represents a side elevation of the blade.

Figure 5 represents a perspective view of a guide plate employed in connection with the blade and guide channel.

Figure 6 represents a horizontal section on line 6—6 of Figure 2, and showing the guide plate in one position.

Figure 7 represents a view similar to Figure 6, but showing the guide plate in another or reversed position.

Figure 8 represents a vertical section similar to Figure 2, but showing in conjunction therewith a novel form of transversely yieldable or floating head to which the blade is connected.

Figure 9 represents a vertical, sectional view taken on section line 9—9 of Figure 8.

Figure 10 represents a horizontal, sectional view on section line 10—10 of Figure 8.

Figure 11 represents a disassembly perspective view, showing the slidable mounting and head of the blade.

Similar numerals of reference indicate corresponding parts.

Referring to the drawings;

1 designates the lower portion of the frame or motor of a fabric cutting machine of the reciprocating blade type, having a bracket 2 provided with a relatively narrow vertical guide standard 3, divided at one edge to provide a blade retaining slot or runway 4, communicating with a guide channel 5, in which blade slot and guide channel, a blade 6 is adapted to reciprocate.

The blade 6 is positioned so that one of its cutting edges 7 projects from the forward edge of the standard 3, above which the vertical, slidable mounting 8, driven from the motor in the usual way, is adapted to recip-

rocate in alignment with said standard and the blade-runway 4 and guide channel 5 which extend longitudinally of and within the standard. The slide or mounting 8 is provided with a head 9 designed to move therewith, and this head projects outwardly in a horizontal position, supported between the two spaced or bifurcated jaws 10 of the mounting 8 and receiving a horizontal pin 11 on which the head is allowed slight lateral play, hereinabove referred to as "floating." The aperture 12 in the head 9 is slightly larger than the pin 11.

The head 9 is further provided with a rigid and integral depending jaw 13 while a removable jaw 14 co-operates with the jaw 13.

A removable jaw 14 cooperates with the jaw 13 and has a threaded shank 15 designed to enter an aperture 16 in the rigid jaw 13 and a pin 17 to enter a hole 18 to retain the separable or detachable jaw 14 against pivotal movement. The opposing faces of the jaws 13 and 14 are roughened or knurled as indicated at 19, so that when the threaded shank 15 is inserted in the aperture 16 to bring the jaws together in assembled relation, a nut or other fastening device 20 may be mounted thereon to firmly clamp the upper end of the blade 6, in a manner shown in Figures 8 and 9.

As before stated, the blade 6 is adapted to reciprocate in the guide channel 5 and blade slot 4 and is provided with opposed longitudinal cutting edges 7 and also provided with cutting edges 21 at its opposite ends, designed to effectively sever the top and bottom layers of the fabric as the machine is advanced along the marks of the piles of fabrics during the cutting action.

The blade 6 is provided at spaced points from each end with rectangular or other polygonal openings 22, pairs of such openings being arranged adjacent but in spaced relation to the cutting edges 7, and these openings are designed to receive rectangular projections 23 extending from one face of a guide plate 24. The guide plate 24 has a flange 25 along its rear edge and when the projections 23 are inserted in the openings 22 of the blade adjacent either one of the cutting edges, in the manner shown particularly in Figure 2 of the drawings, the plate may be inserted in the slot 4, and the guide plate 23 will be accommodated in the channel 5, against the back portion 26, which serves as a reinforcement and wear member at the bright portion of the limb channel. The front edge of the guide plate is in spaced relationship to the front of the channel 5 as indicated at 27, thus preventing wear on that edge of the guide plate and the adjacent wall of the channel, but the guide plate fits against one inner side face of the channel so as to render it possible to thoroughly lubri-

cate the working parts and positively guide the plate in its reciprocating movements in the channel or runway.

In addition, the ends of the guide plate are cut square and substantially form shearing edges which will cut or clear the channel of all foreign matter, splayed out fabric or disintegrated parts thereof, such as would be likely to cause a binding action and restrain the plate from working freely in the channel, thus preventing the breaking, bending, or mutilation of the blades.

The blades, in practice are made of relatively thin material and the cutting edges are often irregular or tortuous and therefore the guide means will serve to positively direct the movements of the blade to accurately cut the cloth or other fabric as the machine is advanced across a table on which the cloth is placed; through the instrumentality of a base 28, to which the lower end of the limb 3 is secured through the medium of the usual foot 29 and which is provided with a recess 30 receiving the lower end of the limb, as is clearly seen in Figure 3 of the drawing.

It may also be stated that the lower end of the blade moves into the foot on its downward stroke in cutting through the fabric, when the cutting edge 21 at the lower end of the blade is particularly effective in use, the lower portions only of the cutting edges 7 are active to cut the cloth and consequently the wear is mainly on these portions, but by reason of the construction of the blade as shown and described, a reversible double edged blade with four cutting portions is provided, thereby augmenting the life and usefulness of the blade.

This is especially due to the fact that the blade can be reversed in respect to its cutting edges and also inverted with respect to its cutting edges 21 at its ends.

Furthermore, by reason of the clamping device including the jaws 13 and 14 and the floating or transversely movable head 9, which compensates for inaccuracies of the cutting edges of the blades, it is unnecessary to provide openings at the ends of the blade to secure it in position for reciprocation, that is, to connect it to the driving means through the medium of the clamping head. This not only makes the construction more economical, but provides a blade having imperforate ends which are disposed at right angles to the longitudinal cutting edges, thereby greatly facilitating the manufacture of the blades.

The guide plate 24 may be reversed in position in the manner shown in Figures 6 and 7 of the drawings, so that the flat portion or body of the guide plate, as indicated at 31, is disposed in contact with both inner faces of the channel 5, thus cleaning both sides of the channel and tending further to prevent any clogging thereof or collection

of gummy or foreign matter upon the inner faces of the channel.

From the construction above described, it will be seen that as the blade is reciprocated, it will be positively guided in its movements, whereby its cutting edge will always work in a direct vertical plane perpendicular to the pile of fabric and the possibility of the blade shifting at an angle either laterally or inwardly is positively prevented by the guide 24, owing to its manner in which the blade is connected to the reciprocating slide, through a floating clamp head. Since the head 9 is allowed a slight lateral play, all angular stresses are eliminated by the transverse or lateral yielding movement of the head between the bifurcated jaws 10 and on the pin 11.

It may also be stated that the aperture 12 is preferably of circular cross section and allows a slight pivotal movement of the head 9 about a horizontal axis, so as to eliminate all torsional stresses or strain which would otherwise tend to break or bend the blade.

As seen particularly in Figure 11 of the drawings, the head 9 is substantially I-shaped in vertical section, thus providing top and bottom flanges 32 to engage above and below the bifurcated jaws or plates 10 and thus to form a firm connection, in a vertical direction between the floating head 9 and the slide member 8 formed integrally with said bifurcated jaws 10, while allowing the necessary universal yielding movements of the head for the purposes above specified.

In the use of the device, the upper end of the blade is inserted between the clamp jaws 13 and 14, after the application of the guide plate 24 and the insertion of the blade together with the guide plate into the slot 4 and the channel 5. The nut 20 is then turned to clamp the blade between the clamp jaws, the knurled faces 19 firmly holding the blade in position. Owing to the slideable mounting of the blade, it will be positively guided in a vertical line so as to give accurate cutting action, and yet, undue stresses to which the blade is subjected in use, both laterally and horizontally, as well as inwardly and longitudinally, will be compensated for by the shifting or floating of the head on its mounting, and thus breaking of or injury to the blade is prevented.

It will now be apparent that I have devised a novel and useful construction in fabric cutting machines, which embodies the features of advantage enumerated as desirable in the statement of the invention and the above description, and while I have in the present instance shown and described the preferred embodiments thereof which have been found in practice to give satisfactory and reliable results, it is to be understood that the same are susceptible of modification in various particulars without departing

from the spirit or scope of the invention or sacrificing any of its advantages.

Having thus described my invention, what I claim as new and desire to secure by Letters Patent, is:—

1. A vertically reciprocable knife for fabric cutting machines having opposed vertical cutting edges and a plurality of openings arranged in a group intermediate said cutting edges.

2. A vertically reciprocable knife for fabric cutting machines having opposed vertical cutting edges and imperforate ends, and a plurality of openings disposed in a group in spaced relation intermediate said cutting edges.

3. A vertically reciprocable knife for fabric cutting machines having an opposed vertical cutting edge and a plurality of cutting corners for said cutting edges.

4. A vertically reciprocable knife for fabric cutting machines having opposed vertical cutting edges and a plurality of openings spaced apart at uniform distances arranged intermediate said cutting edges.

5. A vertically reciprocable knife for fabric cutting machines having opposed vertical cutting edges, imperforate ends and end cutting corners, and a guide plate having projections adapted to detachably engage the knife.

6. A vertically reciprocable knife for fabric cutting machines having opposed vertical cutting edges, imperforate ends and end cutting corners, and a centrally arranged group of openings uniformly spaced from said edges.

7. A vertically reciprocable knife for fabric cutting machines having opposed vertical cutting edges and a plurality of openings spaced from said edges of the knife and a guide plate having projections adapted to enter the openings.

8. A vertically reciprocable blade for fabric cutting machines having vertical cutting edges parallel to each other and a guide plate fitted against and detachably connected to the blade in its length.

9. A vertically reciprocable knife for fabric cutting machines having vertical cutting edges parallel to each other and edges at right angles thereto to form cutting corners, and a guide plate fitted against and connected to the blade in its length, said guide plate having a flange in back of the blade spaced therefrom.

10. A knife for fabric cutting machines having spaced longitudinal cutting edges and opposite pairs of openings intermediate of its ends, and a guide plate fitted against the blade with projections detachably engaged through the openings, and having a flange overlying the back edge of the blade and spaced therefrom.

11. A cloth cutting knife of the character

described, comprising a vertically reciprocable blade having a plurality of longitudinal cutting edges entirely along its longitudinal edges and cutting edges entirely across 5 its ends.

12. A cloth cutting knife of the character described comprising a vertically reciprocable blade having a plurality of longitudinal cutting edges and end cutting edges at 10 right angles thereto entirely across its ends.

13. A vertically reciprocable blade for a fabric cutting machine, having opposed cutting edges and a guide plate mounted on the

blade intermediate of its two ends and adapted to slide within the guide channel of the 15 machine.

14. In a vertically reciprocable blade for a fabric cutting machine, having imperforate ends, and opposed cutting edges, and a guide plate mounted on one side of the 20 plate at its intermediate portion and rigid therewith, said guide plate being adapted to reciprocate in the guide channel of the machine and to prevent clogging thereof.

ISAAC APPELBAUM.
